UNITED STATES PATENT OFFICE

113,214

DESIGN FOR A PINOCHLE SCORING RACK

John W. Bates, Altadena, Calif.

Application November 26, 1938, Serial No. 81,365

Term of patent 14 years

To all whom it may concern:

Be it known that I, John W. Bates, a citizen of the United States and a resident of Altadena, county of Los Angeles, State of California, have invented a new, original, and ornamental Design for Pinochle Scoring Rack, of which the following is a specification, reference being had to the annexed drawing, forming a part thereof.

Fig. 1 is a perspective view of a pinochle scoring rack showing my design; and
Fig. 2 is a plan view thereof.

I claim:

The ornamental design for a pinochle scoring rack, as shown.

JOHN W. BATES.
